CENTRALIZED TRAFFIC CONTROLLING SYSTEM FOR RAILROADS

Original Filed May 24, 1933 3 Sheets-Sheet 1

<img alt="Circuit diagram of a control system for a motor or pump. The diagram shows various logic gates (NAND, NOR, and inverter symbols) connected to form a complex control logic. Key components include a 555 timer (labeled 555) with pin 14 connected to ground, a 556 timer (labeled 556) with pin 14 connected to ground, and a 553 timer (labeled 553) with pin 14 connected to ground. The circuit includes a power supply section with 12V, 5V, and 3.3V outputs, and a ground connection. Various pins are labeled with numbers such as 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 6630, 6631, 6632, 6633, 6634, 6635, 6636, 6637, 6638, 6639, 6640, 6641, 6642, 6643, 6644, 6645, 6646, 6647, 6648, 6649, 66410, 66411, 66412, 66413, 66414, 66415, 66416, 66417, 66418, 66419, 66420, 66421, 66422, 66423, 66424, 66425, 66426, 66427, 66428, 66429, 66430, 66431, 66432, 66433, 66434, 66435, 66436, 66437, 66438, 66439, 66440, 66441, 66442, 66443, 66444, 66445, 66446, 66447, 66448, 66449, 664410, 664411, 664412, 664413, 664414, 664415, 664416, 664417, 664418, 664419, 664420, 664421, 664422, 664423, 664424, 664425, 664426, 664427, 664428, 664429, 664430, 664431, 664432, 664433, 664434, 664435, 664436, 664437, 664438, 664439, 664440, 664441, 664442, 664443, 664444, 664445, 664446, 664447, 664448, 664449, 6644410, 6644411, 6644412, 6644413, 6644414, 6644415, 6644416, 6644417, 6644418, 6644419, 6644420, 6644421, 6644422, 6644423, 6644424, 6644425, 6644426, 6644427, 6644428, 6644429, 6644430, 6644431, 6644432, 6644433, 6644434, 6644435, 6644436, 6644437, 6644438, CENTRALIZED TRAFFIC CONTROLLING
SYSTEM FOR RAILROADS

Neil D. Preston, Rochester, N. Y., assignor to General Railway Signal Company, Rochester, N. Y.

Application May 24, 1933, Serial No. 672,652
Renewed January 3, 1938

13 Claims.

(Cl. 246—5)

This invention relates to systems for governing traffic on railroads and it more particularly pertains to systems known as centralized traffic controlling systems.

- 5 In a centralized traffic controlling system of the type contemplated by this invention, communication is established between a central control office and a number of outlying field stations by means of a station selective coded type of communication 10 system. In a communication system of this type, a plurality of series of impulses of different code combinations are transmitted over the line circuit connecting the control office and the field stations. The first portion of each different series 15 of code combinations is employed for selecting the stations, while the later portion of each different series of code combinations is employed to control the traffic controlling devices at the selected station.
- 20 A centralized traffic controlling system in which the present invention is useful, has the switches and signals at various stations along a railroad system placed under the control of an operator in the control office in such a way that he may change the positions of the switches, subject to 25 automatic approach and detector locking circuits which prevent unsafe operation of any switch. He may also hold any of the signals "at stop" or allow them to clear, dependent upon the positions 30 of the associated switches and also provided the location of trains makes it safe for a signal to indicate proceed.

In a centralized traffic controlling system of the type contemplated by this invention, various indications are displayed in the control office to indicate the presence or absence of trains on the various track sections and to indicate the operated positions of the various switches, signals and the like.

In a system as above outlined, the various 40 switches and signals at the passing sidings or the like which are distributed throughout the territory are grouped in what may be conveniently termed field stations, which usually include those traffic controlling devices located near or adjacent each other. The communication system 45 which interconnects the control office with the various field stations for the transmission of controls and indications is preferably of the coded duplex type, as disclosed for example in the pending application of Judge and Bushnell, Ser. No. 640,062 filed October 28, 1932, corresponding to British Patent 419,399. A communication system of this type is operable through cycles of 50 operation during which a code call is transmitted for the selection of the desired station, after which the controls are transmitted to the individual traffic controlling devices at that station.

55 Since the present invention is particularly directed to the transmission of outbound controls and since the operation of the system in connec-

tion with the transmission of inbound indications is thoroughly disclosed in the above mentioned application No. 640,062, the present description will be directed entirely to the transmission of outbound calls from a typical control office to a typical field station. 5

In the case of a field station having two track switches, for example, with the necessary signals for governing traffic thereover, there are six possible routes over the track switches which may be 10 set up in different combinations at any one time. Where the number of switches and signals in a track layout at one location is more than can be conveniently controlled in one operating cycle, it becomes necessary to provide some means to prevent clearing signals over wrong routes. For example, referring to the typical arrangement of two switches shown in Fig. 3 and assuming that switch 1TS is in its reverse position, switch 2TS is in its normal position and that the operator desires to clear the route over both switches reversed. Under these conditions, if a control code is transmitted to clear signal 1AE, this signal may show clear before switch 2TS is reversed thereby displaying the wrong route indication. A feature of 15 the present invention contemplates checking the reception of switch controls before permitting 20 clearing of signals. 25

In the present invention, it is proposed to arrange a portion of the cycle for the transmission 30 of a message indicating whether or not a switch lever in the control office has been shifted to a new position so that transmission, proper execution and registration of the switch controls must occur before a signal can clear. More specifically, 35 if a switch lever has been moved to a new position, one cycle of operations is effective to select a particular field station and to transmit a code combination for preparing the proper signal clearing circuit at the selected station. Thereafter 40 an additional cycle is effective for controlling the switches at the selected station and for completing the signal clearing circuit. 45

In many cases the signals may be cleared over a particular route without operating any of the 45 switches to new positions. In this event it is undesirable to transmit a cycle for controlling switches and a further feature of the present invention contemplates the operation of the system through only one operating cycle if signals 50 are to be cleared without the operation of any switch or switches. Such an operating cycle is effective to transmit signal controls alone.

These characteristic features of the invention thus briefly stated will be explained more in detail in the following description of one embodiment and the various functions and advantages 55 of a system employing this invention will be in part pointed out and in part apparent as the description progresses. 60

In the accompanying drawings, the invention has been shown applied to a track layout at a single location having two track switches and associated signals but it should be understood that 5 the invention is not limited as thus shown, since it may be readily applied to all types and combinations of track layouts.

In describing the invention in detail, reference will be made to the accompanying drawings in 10 which similar parts throughout the several views are designated by similar reference characters, some of which are provided with distinctive exponents to indicate the location of the associated apparatus in the system and some of which are 15 provided with distinctive ordinals to indicate the order of operation of the particular device with which the reference character is associated and in which:—

Fig. 1 illustrates the apparatus and circuit arrangement provided as a portion of a typical control office equipment constructed and arranged according to the present invention.

Figs. 2 and 3 when placed end to end, illustrate the apparatus and circuit arrangement employed at a typical field station for providing the control of a plurality of track switches and signals at a single location in accordance with the present invention and adapted to be associated with the apparatus employed in the control office.

30 In considering the detailed operation of the system employed in the embodiment of the present invention, Fig. 1, Fig. 2 and Fig. 3 should be placed end to end in the order named with correspondingly numbered lines in alignment.

35 For the purpose of simplifying the illustrations and facilitating in the explanation, the various parts and circuits have been shown diagrammatically and certain conventional illustrations have been employed, the drawings having been 40 made more with the purpose of enabling a clear understanding of the principles and mode of operation to be obtained, rather than with the idea of illustrating the specific construction and arrangement of parts that would be actually employed in practice. The various relays and their 45 contacts are illustrated in a conventional manner and symbols are used to indicate the connections to the terminals of batteries or other suitable sources of current, instead of showing 50 all of the wiring connections to these terminals.

The symbols (+) and (−) indicate the positive and negative terminals respectively of suitable batteries or other sources of direct current and the circuits with which these symbols are 55 used always have current flowing in the same direction. The symbols (B+) and (B−) indicate connections to the opposite terminals of a suitable battery or other direct current source which has an intermediate tap (CN) and the 60 circuits with which these symbols are used may have current flowing in one direction or the other, depending upon the particular terminal used in combination with the intermediate tap (CN).

65 *Communication system in general.*—For the transmission of controls, a transmitting equipment is located in the control office and a receiving equipment is located at each of the various field stations. These receiving equipments are connected to the transmitting equipment by 70 a suitable communication line circuit comprising a control line and a return line. In the drawings, the control line is identified by the reference character 10 and the return line by the reference character 12. The control line circuit is used 75 for the transmission of impulses from the con-

trol office and includes a three-position polarized biased-to-neutral line relay F in the control office and a similar relay F¹ at each field station.

The transmission of a series of distinctive impulses over the control line circuit results in the 5 synchronous step-by-step operation of a stepping relay bank at the control office and at each field station, irrespective of the polarity of the impulses. The polarity of the impulses determines the particular field station to be selected 10 during the first part of the operating cycle, while the polarity of the impulses during the later part of the operating cycle determines the controls to be transmitted to the selected field station.

15 For the transmission of indications to the control office, only one field station at a time is permitted to transmit over the indication line circuit during any particular operating cycle as determined by some suitable lock-out arrangement. This selection of a field station for permitting it to transmit indications is immaterial 20 for an understanding of the present invention and therefore has been omitted.

25 *Control office equipment.*—The control office (see Fig. 1) includes a control machine having a group of control levers for each field station, together with suitable apparatus and circuits to accomplish proper functioning of the system. Fig. 1 illustrates diagrammatically only a portion of such a control machine, which is typical 30 of the apparatus associated with a track section comprising two track switches as illustrated in the upper right hand portion of Fig. 3.

35 The apparatus for the two track switches comprises switch machine control levers 1SML and 2SML, a signal control lever SGL and a self-restoring starting button SB. The movement of a switch machine control lever to one extreme position or the other results in the normal or reverse operation of the corresponding track switch 40 at the corresponding field station through the medium of the communication system. The movement of the signal control lever from its intermediate or full line position shown in Fig. 1 (which corresponds to signals "at-stop") to the right or 45 left dotted positions clears a signal for traffic over the associated track switch in an eastbound or a westbound direction respectively, through the medium of the communication system.

50 The movement of the signal control lever and the subsequent operation of the associated starting button without the movement of an associated switch machine lever, results in a single 55 cycle of operations of the communication system, during which a code combination of one class is transmitted and the signal is cleared at the end of the cycle. If one or both of the switch machine levers is actuated and the signal lever is positioned to clear a signal, followed by the operation of the starting button, then the code 60 combination is transmitted to the selected field station for preparing the signal clearing circuit during a first cycle of the communication system. No switch machine control is transmitted during this first cycle under this condition, but the system goes through a second cycle during which the transmission of a code combination of another class takes place which includes switch controls. The signal clearing circuit is completed 65 at the end of the second cycle.

70 Checking relay WCK, normally energized over its stick circuit, is dropped when a cycle is initiated during which switch controls are to be transmitted as determined by a change in the position of a switch machine lever. Signal 75

change or starting relay SGCH picks up when the associated starting button is actuated and stores the condition that the associated station is to be selected. Switch change or starting relay SMCH is picked up to store the condition that a lever has been moved from one position to another. In other words, these two starting relays when picked up cause the communication system to go through cycles of operations, only one cycle being effected if relay SGCH is picked up alone, while two cycles are effected if both relays SGCH and SMCH are picked up to initiate the system.

Signal code determining relay SGCD and switch machine code determining relay SMCD associated with a particular field station are controlled by their respective change relays in such a way that the signal code determining relay determines the code combination which is transmitted during the first cycle and the switch machine code determining relay determines the combination which is transmitted during the second cycle. The interlocking circuits of these two relays are such that only one of them can be picked up at any one time, with relay SGCD having preference. Relays EP, FP, 2FP, SA, 2SA, PC, NC and C correspond to similar relays in the above mentioned prior application Ser. No. 640,062 and since the operation of these relays, as well as the operation of the stepping relay bank, has been thoroughly explained in this prior application, a detailed description of their functioning will not be given here.

The control office equipment also includes a line battery CB for supplying positive and negative potential to the line circuit in accordance with the positions of positive control relay PC and negative control relay NC.

Field station equipment.—With reference to the typical field station equipment shown in Figs. 2 and 3, two turn-out tracks have been shown controlled by means of track switches 1TS and 2TS. These track switches are suitably controlled from one extreme position to the other by suitable switch machines (not shown) such for example, as in the patent to W. K. Howe, No. 1,466,903 dated September 4, 1923. These switch machines are in turn controlled by switch machine relays 1SMR and 2SMR, subject to suitable approach locking means and since the detailed circuit arrangements for this control is immaterial to an understanding of the present invention, the control of the track switches through the medium of the switch machines has been merely indicated by means of dotted lines extending from the contacts of the switch machine relays to their associated track switches.

The positions of the track switches are indicated by the usual switch repeating relays 1WP and 2WP which are of the polar neutral type, energized with a particular polarity so that their polar contacts are positioned to the right when the associated switch machine is in its normally locked position and to the left when the corresponding switch machine is in its reverse locked position. The neutral contacts of these relays drop to their deenergized positions when the corresponding switch is unlocked or is in operation. These switch repeating relays are likewise indicated as being controlled from the corresponding track switches by means of dotted line connections instead of showing the detailed circuit arrangements of such control.

Associated with the track section is the usual track relay T and track repeating relay TP. Sig-

nals 1E and 1AE govern eastbound traffic over the track switch 1TS over the main track and onto the turn-out track respectively. Signal 1W governs west-bound traffic over the main track, signal 1AW governs westbound traffic over the center track onto the main track and signal 1BW governs traffic over the upper track onto the main track by way of the center track.

Each signal is associated with a signal control relay, for example, the signal control relays 1EG and 1AEG clear signals 1E and 1AE respectively when these relays are picked up and when they are dropped the corresponding signals are put to stop. Likewise, relays 1WG, 1AWG and 1BWG clear signals 1W, 1AW and 1BW respectively when these relays are picked up and the respective signals are put to stop when the corresponding relays are dropped.

The signal control relays 1EG, 1AEG, 1WG, 1AWG and 1BWG are governed from the control office through the medium of the communication system. Each signal relay is dependent for its energization upon the traffic direction relay TD being properly positioned, as well as proper correspondence between the switch relays and the switch machine repeating relays.

When all of the signals are at stop, relay M is energized through a circuit which includes back contacts on each of the signal control relays. Checking relay CK, normally energized by means of its stick circuit, permits clearing of signals during a cycle for the transmission of signals alone. This relay is dropped during a signal control cycle if this cycle is to be followed by a switch control cycle, so that clearing of signals is prevented in this case until the proper switch controls have been transmitted.

Clearing relay CL is for the purpose of energizing the signal clearing circuit and when this relay is picked up it is stuck up until the associated track section becomes occupied or until a stop signal code is transmitted for picking up stop relay SP. Signal station relay SGST and switch machine station relay SMST correspond to the signal code determining and switch machine code determining relays respectively in the control office, since relay SGST is picked up during a cycle for the transmission of signal controls and relay SMST is picked up during a cycle for the transmission of switch controls. Code receiving relays 1PC, 2PC and 3PC record the positive impulses applied to the control line and code receiving relays 1NC, 2NC and 3NC record the negative impulses applied to the control line, these relays being selected on the first three steps after station selection by means of stepping relays 3V¹, 4V¹ and 5V¹. These code receiving relays record the polarity of the code impulses and by means of circuits made up through their contacts, proper selection is made of the various control relays, all of which will be pointed out in the detailed description.

Executing relay EX is picked up on the sixth step, which step follows the registration of the code which positions the code receiving relays. Relay EX controls certain detailed executing circuits as will be more clearly explained in connection with the detailed description.

Relays FP¹, SA¹ and the stepping relays correspond to similar relays in the above mentioned prior application Ser. No. 640,062 and since the operation of these relays may be the same as disclosed in this prior application, a detailed discussion relating to this portion of the system will not be given here.

It is to be understood that although the field station has not been shown as having indication transmitting means nor has the control office been shown as having indication receiving means, a complete system as contemplated to be employed in accordance with the present invention would have such features. However, for the purpose of describing the present invention, such features are considered as immaterial.

10 It is believed that the nature of the invention, its advantages and characteristic features can be best understood with further description being set forth from the standpoint of operation.

Operation

15 The system is normally at rest but may be initiated by the operator for the transmission of controls in the manner fully set forth in the above mentioned prior application, Ser. No. 640,062. Front contact 27 on relay SGCH of Fig. 1 corresponds to front contact 27 on relay 1CH of Fig. 5 in the above mentioned prior application and since front contact 28 on relay SMCH of Fig. 1 is in multiple with front contact 27, the picking up of either one or both relays SGCH and SMCH initiates the system.

20 It will be assumed that the system steps through cycles of operations as long as one of these change relays is picked up and an explanation will be given of the features and operation of the present embodiment which more particularly pertains to the transmission of controls to a selected station after the station selecting steps have been marked off. In this connection, it is assumed that the station illustrated in Figs. 30 2 and 3 is selected on the first two steps of the cycle and that the third, fourth, fifth and sixth steps are employed for the transmission of the code combinations to the selected station.

35 40 With the possibility of having either a posi-

tive or a negative impulse for each step of the communication system, the number of code combinations is equal to two (2) raised to the power of the number of steps. In the present illustration, three steps have been employed for the 5 route control codes and with the impulses for these three steps arranged in code combinations, eight different codes are used, two of which are in the group of combinations conveniently referred to as of the first class, that is, where the 10 communication system steps through only one cycle of operations. The remaining six code combinations are conveniently referred to as of the second class, in which the communication system steps through two cycles of operation for 15 each code combination.

By referring to the table given below, it will be noted that the first code (third step) is always (+) for the first cycle and (-) for the second cycle. The second code (fourth step) is (+) for 20 the combinations of the first class, as determined in the control office by the fact that no switch machine lever is moved to a new position and repeated at the field station by maintaining the checking relay in its picked up position. The 25 second code of the first cycle is (-) when a switch machine lever is moved to a new position requiring the transmission of a second series of impulses. The third code (fifth step) is (+) or (-) for the first cycle as determined by the direction of traffic to be cleared at the field station.

30 The second code (fourth step) of the second cycle is (+) or (-) as determined by switch machine lever 1SML in its normal position or its reverse position respectively. The third code impulse (fifth step) of the second cycle is (+) or (-) as determined by switch machine lever 2SML being in its normal position or its reverse position respectively.

35 40

Table of code combinations (first class)

Code number	Third step	Fourth step	Fifth step	Code use
1-----	+	+	+	No switch lever changed. Clear signal east.
2-----	+	+	-	No switch lever changed. Clear signal west.

Table of code combinations (second class)

Code number	Third step	Fourth step	Fifth step	Code use
1. 1st cycle-----	+	-	+	Switch lever changed. Select signal east.
	-	+	+	Position switch No. 1 normal. Clear signal east.
2. 1st cycle-----	+	-	-	Switch lever changed. Select signal west.
	-	+	+	Position switch No. 1 normal. Clear signal west.
3. 1st cycle-----	+	-	+	Switch lever changed. Select signal east.
	-	-	+	Position switch No. 1 reverse (No. 2 normal). Clear signal east.
4. 1st cycle-----	+	-	-	Switch lever changed. Select signal west.
	-	-	+	Position switch No. 1 reverse (No. 2 normal). Clear signal west.
5. 1st cycle-----	+	-	+	Switch lever changed. Select signal east.
	-	-	-	Position switch No. 1 reverse (No. 2 reverse). Clear signal east.
6. 1st cycle-----	+	-	-	Switch lever changed. Select signal west.
	-	-	-	Position switch No. 1 reverse (No. 2 reverse). Clear signal west.

Station selection and step-by-step operation.—

At the beginning of the cycle relay FP is energized by polar contact 67 in either a right or a left hand position, depending upon the polarity of which line 19 is energized. The closure of front contact 68 of relay FP energizes relay 2FP which in turn energizes the slow acting relay SA by closing front contact 69. Relay SA picks up after a short time interval and closes a circuit by way of its front contact 10 for picking up relay 2SA. Relays SA and 2SA remain picked up throughout the cycle of operations until a predetermined period of time after the control line has been deenergized at the end of the cycle.

Relays F¹, FP¹, SA¹ and SO¹ at the field station are picked up at the beginning of the cycle. Relay FP¹ repeats the impulses in the line circuit irrespective of their polarity while relay F¹ is positioned to the right by a (+) impulse and to the left by a (-) impulse. Relay SO¹ remains picked up at the selected station until the end of the cycle and relay SA¹ remains picked up until a predetermined period of time after the control line has been deenergized at the end of the cycle.

Upon the first deenergization of the control line (following its first energization) as repeated by relays FP and FP¹, the first stepping relay is picked up and similarly, during each following deenergized condition of the control line a succeeding stepping relay is picked up, so that after the station has been selected by the continued energization of relay SO¹, the control steps are then taken which include stepping relays 3V¹, 4V¹, 5V¹ and 6V¹ at the selected station. It will be understood that relays SGCD and SMCD have multiple sets of contacts so that either one picked up controls station selection during the first steps of the cycle in the same manner that relay 1CD controls the selection of a station in the above mentioned prior application Ser. No. 640,062.

Single signal clearing cycle.— It will now be assumed that the operator desires to clear signal 1E for traffic over the main track in an eastward direction (see Fig. 3). Since switch machine levers 1SML and 2SML are in their normal positions, track switches 1TS and 2TS will be assumed to be in their normal positions. In this event, it is not necessary to operate a switch machine lever so that the operation of signal lever SGL to its right dotted line position is effective to transmit a code for clearing signal 1E on a single cycle.

After lever SGL is moved to its right position, the starting button SB is actuated which closes a circuit for picking up relay SGCH which extends from (+), front contact 11 of button SB and winding of relay SGCH, to (-). Relay SGCH closes a stick circuit for itself extending from (+), back contact 13 of relay SGCD, front contact 14 and winding of relay SGCH, to (-). The closing of front contact 27 initiates the cycle of operations as above noted.

A circuit is closed for picking up relay SGCD extending from (+), back contact 15 of relay SA, back contact 16 of relay NC, back contact 11 of relay PC, front contact 18 of relay SGCH and winding of relay SGCD, to (-). The opening of back contact 18 of relay SGCH prevents the energization of any other CD relay, including relay SMCD in the series but farther along the chain circuit, in the event that another change relay is picked up such as relay SMCH.

In other words, if two or more change relays are up at the same time, the signal code determining relay such as relay SGCD nearest the (+) end of the circuit including conductor 19 has preference.

The picking up of relay SGCD closes a stick circuit for itself extending from (+), back contact 20 of relay 2SA, back contact 21 of relay SMCD, front contact 22 and winding of relay SGCD, to (-). Since relay SA is picked up before relay 2SA, this stick circuit is maintained energized through front contact 23 of relay SA after the picking up of relay 2SA, so that relay SGCD remains stuck up until the end of the cycle. Since relay SA is dropped before relay 2SA at the end of the cycle, this stick circuit is deenergized for a sufficient period of time to allow relay SGCD to drop.

The picking up of make-before-break contact 13 of relay SGCD transfers the stick circuit of relay SGCH from (+), to (+) through back contact 24 of relay 2FP. When relay 2FP is picked up this stick circuit is deenergized before relay SA picks up its contact 15, so that relay SGCH is deenergized and since front contact 15 of relay SA is immediately closed relay SGCH may again be picked up and stuck up to store the condition that starting button SB has been again actuated.

After the dropping of contact 18 of relay SGCH, the picking up of another CD relay such as relay SMCH is prevented, even though front contact 25 of relay SMCH is closed because the series pick-up circuit including conductor 19 is deenergized at back contact 15 of relay SA.

Assuming relay 3V picked up on the third step, a circuit is closed for picking up relay PC which extends from (+), front contact 41 of relay C (corresponding to front contact 41 of relay C in the above mentioned prior application Ser. No. 640,062), back contact 43 of relay 6V, back contact 44 of relay 5V, back contact 45 of relay 4V, front contact 42 of relay 3V, control bus 61, front contact 46 of relay SGCD, (+) control bus 47 and winding of relay PC, to (-).

The picking up of relay PC preselects (+) for the next energization of the control line, since the (+) terminal of battery CB extends through back contact 50 of relay NC, front contact 51 of relay PC, back contact 52 of relay EP and winding of relay F to line conductor 10. Relay F¹ at the field station is positioned to the right which closes a circuit for picking up relay 1PC extending from (+), front contact 118 of relay SO¹, contact 114 of relay F¹ in its right hand dotted position, back contacts 110, 111 and 112 of relays 6V¹, 5V¹ and 4V¹ respectively, front contact 115 of relay 3V¹ and winding of relay 1PC, to (-). Relay 1PC closes a stick circuit for itself extending from (+), front contact 113 of relay SA¹, front contact 116 and winding of relay 1PC, to (-).

Signal station relay SGST is picked up over a circuit extending from (+), front contact 117 of relay 1PC, back contact 120 of relay 1NC and winding of relay SGST, to (-). Since back contact 117 of relay 1PC is open throughout this cycle, relay SMST cannot be picked up. With relay SMST deenergized, the circuits to the switch machine control relays 1SMR and 2SMR are maintained deenergized so that these relays cannot be operated during a cycle for the transmission of signal controls only.

When relays 4V and 4V¹ are picked up to select the circuits for the fourth step, relay PC

- is again energized over a circuit which now extends through front contact 45 of relay 4V, control bus 71, front contact 49 of relay SGCD and front contact 40 of relay WCK to the (+) control bus 47. The fourth impulse in control line 10 is therefore (+) which positions contact 114 of relay F¹ to the right, closing a circuit which now extends through front contact 112 of relay 4V¹ and the winding of relay 2PC, to (—). 10 Relay 2PC picks up and closes an obvious stick circuit for itself by way of its front contact 121.

When relays 5V and 5V¹ are picked up to select the circuits for the fifth impulse, a circuit is closed for again energizing relay PC extending 15 from (+), front contact 41 of relay C, back contact 43 of relay 6V, front contact 44 of relay 5V, control bus 81, front contact 59 of relay SGCD, contact 56 of lever SGL in its right (east) dotted position, (+) control bus 47 and winding of relay PC, to (—). At the field station, contact 114 of relay F¹ is actuated to the right closing a circuit for picking up relay 3PC which extends from (+), front contact 118 of relay SO¹, contact 114 of relay F¹ in its right hand dotted position, back contact 110 of relay 6V¹, front contact 111 of relay 5V¹ and winding of relay 3PC, to (—). Relay 3PC closes an obvious stick circuit for itself by way of its front contact 122.

When relay 6V is picked up to select the polarity of the sixth impulse in line conductor 10, a circuit is closed for picking up relay NC extending from (+), front contact 41 of relay C, front contact 43 of relay 6V, control bus 91, front contact 57 of relay SGCD, contact 58 of lever SGL in its right dotted (proceed) position, (—) control bus 48 and winding of relay NC, to (—). This causes line 10 to be energized with current of (—) polarity at the sixth step so that relay F¹ is positioned to the left. A circuit is closed 40 for picking up relay CL extending from (+), front contact 118 of relay SO¹, contact 114 of relay F¹ in its left hand dotted position, front contact 123 of relay 6V¹, front contact 124 of relay SGST and winding of relay CL, to (—). Relay CL closes a stick circuit for itself extending from (+), front contact 125 of relay T, back contact 126 of relay SP, front contact 127 and winding of relay CL, to (—).

The executing circuit at the field station is 50 effected on the sixth step when relay FP¹ picks up and closes a circuit for picking up relay EX extending from (+), front contact 128 of relay FP¹, front contact 129 of relay 6V¹ and winding of relay EX, to (—). A circuit is now closed 55 for positioning direction relay TD to the right extending from (B+), front contact 130 of relay EX, front contact 131 of relay 3PC, back contact 132 of relay 3NC, front contact 133 of relay SGST, conductor 134, front contact 135 of relay M and winding of relay TD, to (CN).

Since it is assumed that track switches 1TS and 2TS are in their normal lock positions, the polar contacts of relays 1SMR, 1WP, 2SMR and 65 2WP are in their right hand positions with the neutral contacts of the WP relays in their energized positions. A circuit is now closed for picking up relay 1EG which extends from (+), front contact 136 of relay CK, conductor 137, front contact 138 of relay 1WP, polar contact 70 139 of relay 1WP in its right hand position, polar contact 140 of relay 1SMR in its right hand position, winding of relay 1EG, polar contact 141 of relay TD in its right hand position, conductor 142 and front contact 143 of relay

CL, to (—). Relay 1EG clears signal 1E by means of its contact 144.

The picking up of back contact 145 of relay 1EG opens the series energizing circuit of relay M, so that this relay is dropped and at its front contact 146 (CN) potential is removed from relays 1SMR and 2SMR so that all switch control circuits are locked to prevent their energization or switch movement when a signal is cleared. The dropping of front contact 135 of relay M 10 opens the energizing circuit of relay TD to prevent a change in the direction selecting circuit when a signal is cleared. The dropping of back contact 147 of relay M connects (+) to conductor 137, which provides a stick circuit for maintaining the signal clear in the event that relay CK is dropped on a subsequent cycle, for a purpose which will be later pointed out.

The passage of an eastbound train over the detector track section in acceptance of the cleared 20 signal 1E deenergizes track relay T, which opens front contact 148 deenergizing track repeating relay TP and thereby closing back contact 149. The opening of front contact 125 of relay T deenergizes the stick circuit of relay CL so that 25 this relay has time to drop before the closure of back contact 149 of relay TP.

The dropping of relay CL deenergizes conductor 142 which is effective to drop relay 1EG for putting signal 1E to stop. The closure of back 30 contact 149 of relay TP prepares the stick circuit for relay CL, so that this clearing relay may be stuck up on a succeeding cycle if relay T is down. The closure of back contact 145 of relay 1EG again completes the energizing circuit 35 for relay M so that this relay picks up and places the circuits in condition for receiving and executing subsequent controls subject of course to approach locking and other safeguards ordinarily provided in a system of this type.

Having considered the manner in which code receiving relays 1PC, 2PC and 3PC are picked up during a cycle of operations in accordance with the code received and the specific manner in which controls result from the execution of the 45 signal clearing circuit for signal 1E, the execution of the remaining codes may be taken up individually with the conditions established prior to the execution impulse being merely mentioned.

Other single signal clearing cycles.—For example, when signal lever SGL is actuated to its left dotted (west) position with levers 1SMR and 2SMR remaining in their normal positions, the actuation of starting button SB initiates the cycle as before. In this event signal 1W at the field 50 station is to be cleared since it is assumed that the track switches 1TS and 2TS are in their normal positions.

The operation is the same as before except that direction relay TD of Fig. 3 is positioned to the 60 left for selecting signal relay 1WG. With contact 56 of lever SGL closed in its left dotted position, the fifth stepping relay 5V selects relay NC so that the fifth impulse applied to line 10 is (—) for positioning relay F¹ to the left. On 65 the fifth step at the field station a circuit is closed from (+), front contact 118 of relay SO¹, contact 114 of relay F¹ in its left hand dotted position, back contact 123 of relay 6V¹, front contact 150 of relay 5V¹ and winding of relay 70 3NC, to (—). Relay 3NC is picked up and stuck up over an obvious circuit closed by its front contact 151.

In this case relays 1PC, 2PC and 3NC are up when the executing impulse is applied to relay 75

EX, so that the actuation of the contacts of relay EX closes a circuit for positioning relay TD to the left extending from (B-), front contact 152 of relay EX, back contact 153 of relay 3PC, front contact 132 of relay 3NC, front contact 133 of relay SGST, conductor 134, front contact 135 of relay M and winding of relay TD, to (CN). When relay CL is picked up as previously described, a circuit is completed for picking up relay 1WG which extends from (+), front contact 136 of relay CK, conductor 137, front contact 138 of relay 1WP, contact 139 of relay 1WP in its right hand position, contact 140 of relay 1SMR in its right hand position, winding 15 of relay 1WG, contact 141 of relay TD in its left hand dotted position, conductor 142 and front contact 143 of relay CL, to (-).

The picking up of back contact 154 of relay 1WG drops relay M for locking as previously described. The actuation of contact 155 of relay 1WG clears signal 1W as indicated by the dotted line connection. The remainder of the operation for this condition is the same as the first detailed example and need not be repeated.

25 For example, with switch machine lever 1SML already in its left dotted (reverse) position and lever SGL positioned to its right (east) dotted position, followed by the actuation of starting button SB, then the cycle of operations is similar 30 to the first detailed example except in this case track switch 1TS will be in its reverse position and relays 1SMR and 1WP will be actuated to the left. In this example signal 1AE is to be energized to clear traffic in an eastward direction 35 over track switch 1TS reversed.

When stepping relay 5V selects contact 56 of lever SGL the circuit is extended to relay PC for applying a (+) impulse to the control line on the fifth step.

40 This (+) impulse actuates relay F¹ to the right as before so that relay 3PC will be picked up. Relay TD is positioned to the right as before so that a circuit is closed for picking up relay 1AEG which extends from (+), front contact 136 of relay CK, conductor 137, front contact 138 of relay 1WP, contact 139 of relay 1WP in its left hand dotted position, contact 156 of relay 1SMR in its left hand dotted position, winding of relay 1AEG, contact 157 of relay TD in its right hand position, front contact 158 of relay 2WP, conductor 142 and front contact 143 of relay CL, to (-). Contact 182 of relay 1AEG clears signal 1AE and contact 177 locks the control circuits as before.

55 For example, with switch machine levers 1SML and 2SML both in their left (reverse) positions and track switches 1TS and 2TS in their reverse locked positions, then the actuation of lever SGL to its right (east) dotted position is likewise effective to clear signal 1AE in the manner just described. In this case the only difference in the control relay positions at the field station is that relays 2SMR and 2WP are in their left hand dotted positions which does not change the above described selecting circuit for relay 1AEG.

For example, if the operator desires to clear signal 1AW when track switch 2TS is normal and 1TS is reverse, switch machine lever 2SML will be in its right (normal) position and lever 1SML in its left (reverse) position. The actuation of lever SGL to its left (west) position followed by the actuation of starting button SB causes the system to go through a cycle of operations as before. In this event, relay 5V selects negative code relay NC through contact 56 of

lever SGL in its left dotted position. This makes the fifth impulse in the line circuit (-) which positions relay F¹ to the left for picking up relay 3NC as previously described.

Relay 3NC picked up and relay 3PC down completes the executing circuit for positioning relay TD to the left when relay EX is picked up to close its front contact 152, which circuit has been previously described. With relay TD positioned to the left, a circuit is closed for picking up relay 1AWG which extends from (+), front contact 136 of relay CK, conductor 137, front contact 138 of relay 1WP, contact 139 of relay 1WP in its left hand dotted position, contact 156 of relay 1SMR in its left hand dotted position, contact 159 of relay 2WP in its right hand position, contact 160 of relay 2SMR in its right hand position, winding of relay 1AWG, contact 157 of relay TD in its left hand dotted position, front contact 158 of relay 2WP, conductor 142 and front contact 143 of relay CL, to (-). Contact 184 of relay 1AWG clears signal 1AW and contact 183 locks the control circuits as before.

For example, if the operator desires to clear signal 1BW, signal lever SGL is operated to its left (west) dotted position and assuming that track switches 2TS and 1TS are both in their reverse locked positions, and assuming that switch machine levers 1SML and 2SML are in their left (reverse) positions, the system steps through a 30 cycle as before. Since contact 56 of lever SGL is in its left dotted position, stepping relay 5V selects relay NC so that the fifth impulse applied to the line is (-). This is effective to pick up relay 3NC instead of relay 3PC and when executing relay EX is picked up at the end of the cycle, relay TD is positioned to the left as previously described. When relay CL is picked up to clear the signal, a circuit is closed for picking up relay 1BWG which extends from (+), front contact 136 of relay CK, conductor 137, front contact 138 of relay 1WP, contact 139 of relay 1WP in its left hand dotted position, contact 156 of relay 1SMR in its left hand dotted position, contact 159 of relay 2WP in its left hand dotted position, contact 161 of relay 2SMR in its left hand dotted position, winding of relay 1BWG, contact 157 of relay TD in its left hand dotted position, front contact 158 of relay 2WP, conductor 142 and front contact 143 of relay CL, to (-). Relay 1BWG clears signal 1BW by actuating its contact 162 and locks the control circuits by actuating its contact 180.

It will be noted that the picking up of any signal clearing relay opens the series energizing circuit of relay M for a purpose which has been 55 already described. The passage of a train over the detector track section in acceptance of a cleared signal causes relays T and TP to be sequentially dropped, which results in the momentary opening of the stick circuit of relay CL so 60 that this relay is deenergized in readiness for preparing the next signal clearing circuit.

In the above recited examples, relay SGCD is picked up when front contact 18 of relay SGCH is closed and the corresponding relay SGST at 65 the field station is picked up due to the fact that the third impulse in the line is (+) for picking up relay 1PC, as determined by relay SGCD being up for selecting relay PC by way of front contact 46 of relay SGCD. Relay 2PC is picked 70 up on the fourth step because relay WCK remains up, so that the fourth impulse is (+) as selected through front contact 40 of relay WCK and front contact 49 of relay SGCD. Relay 3PC is picked up when the fifth impulse is (+) as de- 75

terminated by signal lever contact 56 being in its right (east) dotted position. The combination of relay 3PC up and relay 3NC down positions relay TD to the right for selecting an eastbound signal clearing relay. With relay 3NC picked up on the fifth step, as determined by lever SGL being in its left (west) position, the combination of relay 3NC up and relay 3PC down positions relay TD to the left for selecting a westbound signal clearing relay.

Since contact 58 of lever SGL is in either its right or left dotted positions in the above examples, the sixth impulse is (—) for picking up relay CL on the sixth step to prepare the signal clearing circuit. If the signal lever contact 58 is in its neutral position, then relay PC is selected on the sixth step for making the sixth impulse (+) which is the stop code. A (+) impulse on the sixth step positions relay F¹ to the right to close a circuit for picking up stop relay SP. This circuit extends from (+), front contact 118 of relay SO¹, contact 114 of relay F¹ in its right hand dotted position, front contact 110 of relay 6V¹, front contact 109 of relay SGST and winding of relay SP, to (—). Relay SP opens the stick circuit of relay CL at its back contact 126 so that relay CL is dropped to put all signals to stop by deenergizing conductor 142. Contact 56 of lever SGL in its neutral position connects to the (+) control bus for the purpose of providing an impulse in the line at the fifth step so that the system will take this step when the stop code is transmitted.

Switch operation.—In the above examples it is assumed that neither switch machine lever 1SML nor 2SML are moved to a new position when a cycle is initiated to clear a signal. It will now be assumed that the switch machine levers are moved to new positions and an explanation will be given of the operation of the system.

In this case the system steps through two cycles of operations, the first cycle being effective to select and prepare the signal clearing circuits and the second cycle being effective to condition the switch machine control circuits, after which the signal clearing circuits are completed, provided proper response and correspondence is established between the various control devices at the field station.

For example, it will be assumed that the operator moves switch machine lever 1SML from the reverse position to the normal position and that lever SGL is in its right dotted position for clearing signal 1E. The momentary opening of contact 32 deenergizes the stick circuit of relay WCK, which stick circuit includes front contact 33 of relay WCK, and this relay is dropped. When starting button SB is actuated, relay SGCH is picked to initiate a cycle of operations as previously described.

Since relay WCK is down, a circuit is closed for picking up relay SMCH extending from (+), contact 26 of button SB, back contact 29 of relay WCK, front contact 34 of relay SGCH and winding of relay SMCH, to (—). Relay SMCH closes a stick circuit for itself extending from (+), back contact 36 of relay SMCD, front contact 35 and winding of relay SMCH, to (—). Relay C is picked up to close its front contact 41 by means of circuits which are disclosed and described in the above mentioned prior application Ser. No. 640,062. The system now steps through a cycle with the stepping relays in the control office and at the field station illustrated in Fig. 2 operating in synchronism.

A circuit is closed through front contact 18 of relay SGCH for picking up relay SGCD as previously described. On the first step after station selection (third step) relay PC is picked up to energize the control line with a (+) impulse. This (+) impulse at the field station picks up relay 1PC as before.

Relay 4V selects relay NC on the fourth step by way of back contact 40 of relay WCK, so that the line circuit is energized with a (—) impulse which is effective to pick up relay 2NC over a circuit extending from (+), front contact 118 of relay SO¹, contact 114 of relay F¹ in its left hand dotted position, back contacts 123 and 150 of relays 6V¹ and 5V¹ respectively, front contact of relay 4V¹ and winding of relay 2NC, to (—). Relay 2NC closes an obvious stick circuit for itself by way of its front contact 164.

On the fifth step relay PC is picked up to provide a (+) impulse in the line circuit because contact 56 of lever SGL is in its right dotted position. This causes the energization of relay 3PC at the station since relay F¹ is positioned to the right.

On the sixth step, relay NC is energized to provide a (—) impulse in the line circuit because contact 58 of lever SGL is in a proceed position. This picks up relay CL at the station to prepare the signal clearing circuit as previously described. In this instance, however, the signal clearing circuit cannot be completed because relay CK is dropped on the fourth step. This is because relay SGST is picked up on the third step, since this is a signal clearing cycle and because relay 2NC is picked up on the fourth step due to a switch machine lever having been moved to a new position. With relays SGST and 2NC picked up, the stick circuit of relay CK is deenergized at back contacts 165 and 166 of these respective relays. Since (+) potential is removed from conductor 137 by the dropping of contact 136 of relay CK, the signal clearing circuit is incomplete. At the end of this cycle relay EX is actuated to close the previously described circuit for positioning relay TD to the right due to the fact that relay 3PC is picked up and relay 3NC remains down.

Relay SGCD in the control office is dropped at the end of this cycle as before. Relay SMCD is picked up over a circuit extending from (+), back contact 15 of relay SA, back contact 16 of relay NC, back contact 17 of relay PC, back contact 18 of relay SGCH, front contact 25 of relay SMCH and winding of relay SMCD, to (—). Relay SMCD closes a stick circuit for itself through its front contact 21 which is similar to the previously described stick circuit for relay SGCD.

Since relay SMCH is picked up, its front contact 28 causes the system to be initiated into a second cycle of operations. On the third step of this cycle relay NC is picked up by way of a circuit including front contact 37 of relay SMCD so that the line is energized with a (—) impulse. At the field station, relay F¹ is actuated to the left for picking up relay 1NC over a circuit including front contact 119 of relay 3V¹. Relay 1NC closes an obvious stick circuit for itself by way of its front contact 167.

On the fourth step relay PC is energized over a circuit including front contact 38 of relay SMCD and contact 39 of lever 1SML in its right position. This energizes the line with a (+) impulse so that relay 2PC at the field station is energized over a circuit including front contact 75

112 of relay 4V¹ and contact 114 of relay F¹ in its right hand dotted position.

On the fifth step relay PC is energized over a circuit including front contact 60 of relay SMCD and contact 62 of lever 2SML in its right position. This energizes the control line with a (+) impulse so that relay 3PC is picked up over a circuit including front contact 111 of relay 5V¹ and contact 114 of relay F¹ in its right hand dotted position.

On the sixth step a circuit is closed for picking up relay NC by way of front contact 63 of relay SMCD. The polarity of this impulse is ineffective at the field station because the circuit through contact 114 of relay F¹ in its left hand dotted position and front contact 123 of relay 6V¹ is open at contact 124 of relay SGST, which is deenergized as will be presently explained. This sixth (-) impulse therefore serves no other purpose than to energize the control line so that the apparatus in the control office and at the field station may take the sixth step. Since relay 1PC is down and relay 1NC is up during this cycle, relay SGST is deenergized. Relay SMST is energized over a circuit extending from (+), front contact 120 of relay 1NC, back contact 117 of relay 1PC and winding of relay SMST, to (-).

Relay EX is picked up at the end of this second cycle and a circuit is closed for picking up relay CK which extends from (+), front contact 168 of relay EX, front contact 169 of relay SMST and winding of relay CK, to (-). Relay CK establishes a stick circuit for itself extending from (+), back contact 165 of relay SGST, front contact 170 and winding of relay CK, to (-).

Recalling that relay CL was picked up at the end of the first cycle and since relay CK is picked up at the end of the second cycle, conductors 137 and 142 are both energized so that signal 1AE may be cleared as soon as the switch machine control and repeating relays are in proper correspondence.

The picking up of relay EX closes a circuit for positioning relay 1SMR to its right hand position which extends from (B+), front contact 130 of relay EX, front contact 179 of relay 2PC, back contact 172 of relay 2NC, front contact 173 of relay SMST, conductor 174, winding of relay 1SMR and front contact 146 of relay M, to (CN).

Since relay 3PC is picked up and since relay 3NC is down, a circuit is also closed for energizing relay 2SMR extending from (B+), front contact 130 of relay EX, front contact 131 of relay 3PC, back contact 132 of relay 3NC, front contact 175 of relay SMST, conductor 176, winding of relay 2SMR and front contact 146 of relay M, to (CN). Since it was assumed that lever 2SML was already in its right (normal) position, relay 2SMR is in its right hand position at this time so that the energization of its winding does not shift its contacts.

Relay 1SMR closes a circuit (not shown) for energizing the switch machine motor over its normal operating circuit and when relay 1WP responds by positioning its polar contact 139 to the right and by picking up its neutral contact 138 as an indication that track switch 1TS is in its normal locked position, the circuit for relay 1EG is completed. This circuit extends from (+), front contact 136 of relay CK, conductor 137, front contact 138 of relay 1WP, contact 139

of relay 1WP in its right hand position, contact 140 of relay 1SMR in its right hand position, winding of relay 1EG, contact 141 of relay TD in its right hand position, conductor 142 and front contact 143 of relay CL, to (-). Signal 1E is cleared and the control circuits are locked as previously described.

Consideration of other combinations.—The description above more specifically points out the transmission of two code combinations during two cycles for moving track switch 1TS from reverse to normal, leaving track switch 2TS in its normal position and clearing signal 1E. Any one of the other signals may be similarly cleared in response to the transmission of the proper code combinations as applied to the line circuit in the control office by the corresponding combinations set up by the switch machine and signal levers.

For example, assuming that lever 1SML is moved from its left (reverse) to its right (normal) position, lever 2SML is left in its normal position and lever SGL positioned in its left dotted (west) position, then signal 1W will be cleared for a train to advance over the main track in a westbound direction. In other words, track switch 1TS will be moved to its normal position, track switch 2TS will remain in its normal position and signal 1W will be cleared. During the operation of the first cycle under this condition, code receiving relays 1PC, 2NC and 3NC will be picked up on steps 3, 4 and 5 respectively. This is determined in the control office by relay PC being selected on the third step through front contact 46 of relay SGCD, relay NC being selected on the fourth step through front contact 49 of relay SGCD, and back contact 40 of relay WCK and relay NC being selected on the fifth step through front contact 59 of relay SGCD and contact 56 of lever SGL in its left position.

On the sixth step relay CL at the field station is picked up as previously described and stuck up until the track section becomes occupied or until a stop signal is transmitted. This is brought about by relay 6V in the control office selecting relay NC through front contact 57 of relay SGCD and contact 58 of lever SGL in its proceed position. Relay TD at the field station is positioned to the left as previously explained, since the circuit extends to (B-) at front contact 152 of relay EX by way of back contact 153 of relay 3PC, front contact 132 of relay 3NC and front contact 133 of relay SGST. Relay SGST is picked up during the first cycle because relay 1PC is up. This operation has been previously described.

During the second cycle relays 1NC, 2PC and 3PC will be picked up at the field station as determined by the selecting circuits through front contact 37 of relay SMCD on the third step, front contact 38 of relay SMCD and contact 39 of lever 1SML in its right position on the fourth step and front contact 60 of relay SMCD and contact 62 of lever 2SML in its right position on the fifth step.

Relay 1NC up and relay 1PC down drops relay SGST and picks up relay SMST to mark this as a second cycle. At the end of the second cycle the previously described executing circuit picks up relay EX and closes a circuit from (B+) at front contact 130 of relay EX, front contact 179 of relay 2PC, back contact 172 of relay 2NC, front contact 173 of relay SMST, conductor 174, winding of relay 1SMR and front contact 146 of relay M, to (CN). This positions relay 1SMR

to the right for positioning track switch 1TS to normal. Since relay 2SMR is assumed to be already in its normal position, track switch 2TS will be in a corresponding position.

- 5 Of course, it will be understood that relay CK was dropped during the first cycle and picked up at the end of the second cycle, so that the signal clearing circuit is not completed until the end of the second cycle. This circuit extends 10 from (+), front contact 136 of relay CK, conductor 137, front contact 138 of relay 1WP, contact 139 of relay 1WP in its right hand position, contact 140 of relay 1SMR in its right hand position, winding of relay 1WG, contact 141 of relay 15 TD in its left hand position, conductor 142 and front contact 143 of relay CL, to (-). Relay 1WG is picked up to clear signal 1W and to drop relay M which locks the switch machine control 20 circuits as before.
- 20 For example, assuming that lever 1SML is moved from its normal to its reverse position, that lever 2SML stays in its normal position and lever SGL is actuated to its right (east) dotted position, relays 1PC, 2NC, 3PC and CL will be 25 picked up on steps 3, 4, 5 and 6 respectively. This combination of relays is determined by relay SGCD being up on the third step, relay WCK being down on the fourth step, lever SGL being in its right dotted position on the fifth step and 30 contact 58 being in its actuated (proceed) position on the sixth step.

Relay 1PC up and relay 1NC down selects and operates relay SGST. Relay 2NC picked up with relay SGST picked up drops relay CK. Relay 3PC up and relay 3NC down completes a circuit from (B+), through front contact 130 of relay EX, front contact 131 of relay 3PC and back contact 35 132 of relay 3NC for actuating relay TD to the right.

40 During the second cycle relays 1NC, 2NC and 3PC will be picked up on steps 3, 4 and 5 respectively as determined by relay 3V in the control office selecting relay NC through front contact 31 of relay SMCD, relay 4V selecting relay NC through contact 39 of lever 1SML in its left dotted position and relay 5V selecting relay PC through contact 62 of lever 2SML in its right position. When relay EX is picked up to execute this combination, relay 1SMR is actuated to its 45 left hand position because the circuit from (B-) at front contact 152 of relay EX is established by way of back contact 171 of relay 2PC, front contact 172 of relay 2NC and front contact 173 of relay SMST. Relay 2SMR is energized with 50 (B+), since the circuit through front contact 130 of relay EX is extended through front contact 131 of relay 3PC, back contact 132 of relay 3NC and front contact 175 of relay SMST. The signal clearing circuit is established for clearing 55 signal 1AE by picking up relay 1AEG over a circuit including contact 157 of relay TD in its right hand position, contacts 156 and 139 of relays 1SMR and 1WP in their left hand dotted positions.

60 65 For example, assuming lever 1SML moved from its normal to its reverse position with lever 2SML remaining in its normal position and lever SGL actuated to its left (west) position, then relays 1PC, 2NC, 3NC and CL at the field station will be 70 picked up during the third, fourth, fifth and sixth steps respectively. This is because the third step in the control office selects relay PC through front contact 46 of relay SGCD, the fourth step selects relay NC because contact 40 of relay WCK is 75 dropped, relay 5V selects relay NC because lever

SGL is in its left (west) position and relay 6V selects relay NC because lever SGL is in a proceed position.

Relay 1PC up and relay 1NC down picks up relay SGST to mark this as the first cycle for preparing the signal clearing circuits. Relay 2NC picked up with relay SGST up drops relay CK to prevent clearing a signal until another cycle is transmitted. Relay 3NC up and relay 3PC down positions relay TD to the left (west) over the previously described circuit including front contact 152 of relay EX.

The system now advances through its second cycle when relays 1NC, 2NC and 3PC are picked up. This is because relay NC in the control office is selected on steps 3 and 4 through front contacts 37 of relay SMCD and front contacts 38 of relay SMCD and 39 of lever 1SML in its left dotted position respectively. Relay PC is selected on the fifth step through contact 62 of lever 20 2SML in its right position. Relay SGST is dropped and relay SMST is picked up (at the field station) at the start of the second cycle as previously described and when execution is effected at the end of the second cycle, relay 1SMR is positioned to the left over a circuit extending from (B-), front contact 152 of relay EX, back contact 171 of relay 2PC, front contact 172 of relay 2NC, front contact 173 of relay SMST and over the remainder of the previously described circuit. 30

Relay 2SMR is energized with current of the proper polarity for maintaining this relay in its right hand position over a circuit extending from (B+), front contact 130 of relay EX, front contact 131 of relay 3PC, back contact 132 of relay 35 3NC and front contact 175 of relay SMST over the remainder of the previously described circuit. Since relay TD is positioned to the left a circuit is completed for picking up relay 1AWG extending from (+), front contact 136 of relay CK, 40 conductor 137, front contact 138 of relay 1WP, contact 139 of relay 1WP in its left hand dotted position, contact 156 of relay 1SMR in its left hand dotted position, contact 159 of relay 2WP in its right hand position, contact 160 of relay 45 2SMR in its right hand position, winding of relay 1AWG, contact 157 of relay TD in its left hand dotted position, front contact 158 of relay 2WP, conductor 142 and front contact 143 of relay CL, to (-). Relay 1AWG clears signal 1AW and 50 locks the control circuits as previously described.

For example, assuming lever 1SML moved from its normal to its reverse position with lever 2SML in its reverse position, then relays 1PC and 2NC are picked up on the third and fourth steps of the first cycle for reasons previously explained. Likewise, relay SGST at the station is picked up and assuming lever SGL in its right dotted position, relay PC is picked up on the fifth step which makes the fifth impulse in the line (+) for picking up relay 3PC. In the event that lever SGL is in its left position, then relay NC is picked up for making the fifth impulse in the line circuit (-) which picks up relay 3NC.

With relay 3PC up and relay 3NC down (lever SGL in its east position), the execution circuit closed at the end of the first cycle extends from (B+) through front contact 130 of relay EX, over the previously described circuit to relay TD 70 for positioning this relay to the right. With relay 3NC up and relay 3PC down (lever SGL in its west position), then the executing circuit for relay TD at the end of the first cycle extends from (B-) through front contact 152 of relay 75

EX over the previously described circuit to relay TD.

During the second cycle under these two conditions, relays 1NC, 2NC and 3NC are picked up as determined by relay SMCD having its front contact 37 closed, lever 1SML having its contact 39 closed in the left dotted position and lever 2SML having its contact 62 closed in its left dotted position. At the end of the second cycle the executing circuit is effective to position relay 1SMR to the left (reverse) because the circuit is completed to (B-) at front contact 152 of relay EX by way of back contact 171 of relay 2PC, front contact 172 of relay 2NC and front contact 173 of relay SMST. (B-) is also applied to relay 2SMR from front contact 152 of relay EX by way of back contact 153 of relay 3PC, front contact 132 of relay 3NC and front contact 175 of relay SMST.

20 The signal clearing circuits with the switch machine control and repeating relays in their reverse positions is established through relays 1AEG or 1BWG as determined by the position of polar contact 157 of relay TD. Relay 1AEG will be picked up to clear signal 1AE if contact 157 of relay TD is in its right hand position (east), over a circuit extending from (B+), front contact 136 of relay CK, conductor 137, front contact 138 of relay 1WP, contact 139 of relay 1WP in its left hand dotted position, contact 156 of relay 1SMR in its left hand dotted position, winding of relay 1AEG, contact 157 of relay TD in its right hand position, front contact 158 of relay 2WP, conductor 142 and front contact 143 of relay CL, to (-).

35 The circuit for relay 1BWG which clears signal 1BW extends from (B+), front contact 136 of relay CK, conductor 137, front contact 138 of relay 1WP, contact 139 of relay 1WP in its left hand dotted position, contact 156 of relay 1SMR in its left hand dotted position, contact 159 of relay 2WP in its left hand dotted position, contact 161 of relay 2SMR in its left hand dotted position, winding of relay 1BWG, contact 157 of relay TD in its left hand dotted position and over the remainder of the previously described circuit, to (-).

In the above examples describing the operation when a switch machine lever is moved to a new position, it has been explained that relay WCK is dropped when its stick circuit is momentarily opened by contact 32 or 72 of lever 1SML or 2SML. At the end of a second cycle, relay WCK is picked up when relay SA is dropped and before relay 2SA drops over a circuit extending from (+), back contact 23 of relay SA, front contact 64 of relay 2SA, front contact 65 of relay SMCD and winding of relay WCK, to (-). Relay WCK is then stuck up until the next actuation of a switch machine lever.

60 It has also been explained how the code receiving relays 1PC, 2PC, 3PC, 1NC, 2NC and 3NC are picked up in various combinations and are stuck up. It will be understood that the stick circuit of these relays is deenergized at the end of each cycle when relays 6V¹ and SA¹ are down, opening their front contacts 103 and 113 respectively. It will be obvious that the stop code (that is, (+) on the sixth step) is effective when a switch machine lever has been moved to a new position because (+) on the sixth step of the first cycle picks up relay SP which prevents relay CL being up to clear any signal in the second cycle.

Summary

75 The system of the present invention provides

for the checking and clearing of routes over a plurality of railway track switches at a single station together with the putting to stop of any of these routes by means of combinations of route control codes transmitted over a selective type communication system.

Two neutral code receiving relays are provided at a field station for each control step with all of these code receiving relays assuming normally deenergized positions. One or the other of the code receiving relays for the corresponding step must receive its impulse in order for a code to be transferred from the code receiving relays to the function control relays at the end of an operating cycle.

It will be apparent from the drawings and description that if for some reason neither code receiving relay for a particular step is picked up or if both are picked up the executing impulse at the end of the cycle will be ineffective to energize either station relay to position the traffic direction control relay or to position the switch machine control relays depending upon the step at which such false operation might happen. In other words, the control circuits are dependent upon the proper energization of the code receiving relays so that an open or a short circuit preventing the response of either or resulting in the response of both does not cause improper control operation.

This means that a surge in the line which may effect the picking up of a PC relay (see Fig. 2) at a particular step when the code impulse picks up the corresponding NC relay of that step and vice versa, or the loss of an impulse resulting in the failure to pick up either a PC or an NC relay at a particular step, results in the failure to complete the executing circuit for changing an existing switch position or signal condition.

For example, if relays 1PC and 1NC should both (or neither) be picked up, neither relay CL nor relay SP can be energized to clear a signal or put an existing cleared signal to stop, because relay SGST cannot be energized under this condition. Since relay SMST cannot be picked up, neither switch control relay 1SMR nor 2SMR can be energized.

For example, if relays 2PC and 2NC should both (or neither) be picked up, the executing circuit extending through contact 152 of relay EX is left open either at contact 171 of relay 2PC or contact 172 of relay 2NC. Likewise the executing circuit extending through contact 130 of relay EX is left open either at contact 179 of relay 2PC or contact 172 of relay 2NC.

For example, if relays 3PC and 3NC should both (or neither) be picked up, the executing circuit extending through contact 152 of relay EX is left open either at contact 153 of relay 3PC or contact 132 of relay 3NC. Likewise, the executing circuit extending through contact 130 of relay EX is left open either at contact 131 of relay 3PC or contact 132 of relay 3NC.

Also, the circuits are so arranged that the switch control relays may not be operated to new positions while a signal is clear as governed by the series circuit of relay M controlled by the signal clearing relays.

Another feature of the present invention resides in the manner in which signals may be cleared during a single operating cycle of the communication system by transmitting a code combination of one class, as determined by the condition that no switch machine control lever in the office is moved to a new position. Two operating cycles

are required to clear a signal when a code combination of a second class is transmitted, as determined by the condition that a switch machine control lever in the office is moved to a new position.

Another feature of the present invention resides in the manner in which the signal clearing circuits are prepared but not completed during the first cycle when the communication system advances through two cycles of operation as a result of a switch machine lever being moved to a new position. In this event, the switch control circuits are completed during the second cycle and at the end of this cycle the proper signal is cleared subject to proper response and correspondence of the control circuits of both cycles.

Having thus described a centralized traffic controlling system as one specific embodiment of the present invention, it is desired to be understood that the present form is selected to facilitate in the disclosure rather than to limit the scope of the invention and it is to be further understood that various modifications, adaptations and alterations may be made in the present disclosure to meet the requirements of practice without in any manner departing from the spirit or scope of the present invention except as limited by the appended claims.

What I claim is:

- 30 1. In a centralized traffic controlling system, a control office, a field station, a control level in said office, a signal at said station, a line circuit connecting said office with said station, a clearing relay and a checking relay at said station, means controlled over said line circuit for momentarily closing pick-up circuits for said relays, a stick circuit for said clearing relay controlled by track conditions at said station, a stick circuit for said checking relay controlled by a change in the position of said lever, means jointly controlled by said relays for clearing said signal subject to traffic conditions, and means for thereafter maintaining said signal clear irrespective of the condition of said checking relay.
- 45 2. In combination, a track switch and a plurality of signals for governing traffic over said track switch, a line circuit having a plurality of series of code impulses of different classes transmitted thereover for controlling said track switch and said signals, code receiving relays each responsive to an impulse of said series for receiving and storing said series of impulses, means effective after the reception of a series of impulses of a first class for clearing one of said signals, means responsive to the reception of a series of impulses of a second class for clearing one of said signals only after the reception of a series of impulses of a third class, and means responsive to a series of impulses of a third class for controlling said track switch.
- 55 3. In a normally at rest code type selector system, a plurality of switch control levers, a signal control lever, a starting button, means initiating the communication system into a single cycle of operation to transmit a signal control code in accordance with the position of said signal control lever upon the momentary actuation of said button provided all of said switch control levers have not been moved, and means initiating the communication system into a plurality of cycles of operation for transmission of both switch and signal control codes upon momentary actuation of said button if one of said switch control machines has been moved to a new position.
- 70 4. In a centralized traffic control system of the

character described, the combination with a power-operated track switch and signals at a field location for governing train movement over said switch in its different positions, of switch control means at the field location for governing said switch, a clearing circuit for each signal closed only if said switch is in a position corresponding with its control means, a switch lever and a signal lever in the control office, a code communication system for transmitting signal control and switch control codes on different operating cycles in accordance with the position of said signal lever and switch lever respectively, means operating upon movement of said switch lever to a different position for modifying the signal control code, and means at the field location rendered effective by the transmission of a signal control code so modified for opening the signal clearing circuits for all of said signals until a switch control code is subsequently received to actuate the switch control means.

5. In a centralized traffic control system of the character described for controlling the operation of a plurality of track switches and signals governing train movement over said switches comprising, a plurality of manually operable switch levers in a control office one for each of said switches, a signal control lever in the control office, a communication system of the code type for transmitting on different cycles switch control and signal control codes in accordance with the positions of said switch control and signal control levers respectively, means responsive to the movement of any one of said switch levers to a different position for changing one code element of the signal control code to a particular character, a stick relay at the field location which must be energized to permit clearing of any of said signals, means in the field for momentarily opening the stick circuit of said stick relay upon reception of a signal clearing code having one element thereof changed to said character, and means responsive to the reception of a switch control code for closing a pick-up circuit for said stick relay.

6. A centralized traffic control system for governing from a distant control office by a code transmission system, the position of a plurality of track switches and signals governing train movement over said switches comprising, manually operable switch control levers one for each switch located in the control office, a signal control lever in the control office, a communication system of the code type for transmitting during one operating cycle a switch control code in accordance with the existing position of said switch levers and during another cycle a signal control code dependent upon the position of said signal lever, means responsive to the movement of any one of said switch levers to a different position for modifying in a certain respect the signal clearing code, and means at the field location rendered effective by the reception of a signal clearing code modified in said respect for preventing clearing of a signal until a switch control code is subsequently received.

7. In a centralized traffic control system of the character described for controlling a track switch and signals governing train movement over said switch in its different positions, a switch lever, a signal lever, a normally at rest communication system of the code type for governing operation of said switch during one operating cycle in accordance with the position of said switch lever and for governing the clearing of said signals

45

50

55

60

- 5 during another cycle in accordance with the position of said signal lever, means in the control office for modifying the signal control code transmitted whenever said switch lever is moved to a 5 different position, means at the field location rendered effective by the transmission of a signal control code of said modified character for preventing clearing of a signal until a new switch control code is subsequently received, and 10 manually controlled means in the control office for initiating said communication and causing it to transmit a modified signal control code during one operating cycle and a switch control code during a subsequent operating cycle.
- 15 8. In a system of the character described, a plurality of power-operated track switches and signals governing train movement over said switches to be controlled from a distant control office, switch control means for each switch, a 20 communication system of the code type operable during a switch control cycle to govern said switch control means for all of said switches, clearing circuits for said signals, said clearing circuit for a given signal being closed only if all 25 of said switches and their respective switch control means are in corresponding positions to provide a route for train movement governed by such signal, and means at the field location controllable from the control office over said communication system for opening and maintaining open said clearing circuits for all of said signals until all of said switches are subsequently controlled during a switch control cycle.
- 30 9. In a centralized traffic controlling system for railroads; a field station having a track switch and signals for governing traffic thereover; a control office having a manually operable switch control lever and a manually operable signal control lever; a communication system of the 35 multiple impulse code type for transmitting during one cycle of operation a signal control code in accordance with the position of said signal control lever and the changed condition of said switch control lever, and for transmitting during another cycle of operation a switch control code 40 in accordance with the position of said switch control lever; a clearing relay and a checking relay at said station; a stick circuit for said clearing relay controlled by track conditions at said 45 station; a pick-up circuit for said clearing relay closed upon the reception of a signal control code transmitted with said signal lever in a clearing position; a stick circuit for said checking relay opened upon the reception of a signal control code transmitted following a change in position 50 of said switch control lever before the transmission of a switch control code; a pick-up circuit for energizing said checking relay upon the reception of a switch control code; circuit means 55 for clearing the said signal only when said clearing relay and said checking relay are both energized; and circuit means rendered effective once a signal is cleared for maintaining such signal in a clear condition dependent upon the energized condition of said clearing relay but independently of the condition of said checking relay.
- 60 10. In a centralized traffic controlling system for railroads; a field station having a track switch and signals for governing traffic thereover; a control office having a manually operable switch control lever and a manually operable signal control lever; a communication system of the 65 multiple impulse code type for transmitting different control codes from the control office to the field station; circuit means in the control 70 office for causing said communication system to transmit a signal clearing code with said signal lever in a clear position and said switch lever in an unchanged position since the last transmission of a switch control code, said means causing said communication system to transmit a modified signal clearing code if said switch control lever has been changed in its position since the last transmission of a switch control code; circuit means in the control office for causing 75 said communication system to transmit a switch control code in accordance with the normal or reverse position of said switch control lever following the transmission of every modified signal clearing code transmitted; code receiving means at said station responsive to the reception of a signal clearing code for immediately clearing said signal and responsive to a modified signal clearing code for clearing said signal only after the reception of a switch control code at said station; and code receiving means at said field station responsive to a switch control code for operating said track switch to a position determined by the position of said switch control lever; whereby the reliability of the code type communication system is checked so as to allow the clearing of a signal after a switch lever movement only provided a switch control code is received at the field station.
- 80 11. In a centralized traffic controlling system for railroads; a plurality of track switches at a field station; a control office having a plurality of manually operable switch control levers one for each of said track switches; a communication system of the multiple impulse code type for transmitting different codes from the control office to the field station on different cycles of operation; circuit means for causing said communication system to transmit a particular code on one cycle of operation if any one or several of said switch control levers has been operated to different positions; other circuit means causing said communication system to transmit on another cycle of operation a switch control code characteristic of the positions of said switch control levers, said another cycle of operation following said one cycle of operation; code receiving means at said field station responsive to said particular code; other code receiving means at said field station responsive to said switch control code for controlling said track switches to positions corresponding to their respective switch control levers; signals at said station for governing traffic over said track switches; and circuits for at times clearing said signals, said circuits being closed only after both said code receiving means have responded to their respective codes.
- 85 12. In a centralized traffic controlling system of the character described; a field station having a track switch and signals for governing traffic over such track switch in its different positions; a control office having a manually operable switch control lever operable to normal and reverse positions and a manually operable signal control lever operable to clear or stop 90 positions; a communication system of the multiple impulse code type connecting said control office and said field station for transmitting different codes; signal circuit means at the control office for causing said communication system to transmit a signal clearing or signal stop control code on one operating cycle of said communication system depending upon the position of said signal control lever; switch circuit means effective to cause said communication system to 95

transmit a normal or reverse switch control code on another cycle of operation of said communication system in accordance with the normal or reverse position of said switch control lever; means
5 including a stick relay effective to modify a signal control code irrespective of whether it is a clearing or stop code; a normally closed stick circuit for said stick relay momentarily opened upon each movement of said switch control lever
10 to a different position; a pick-up circuit for said stick relay closed momentarily upon the transmission of each switch control code; means at the field station responsive to the reception of a signal clearing or stop control code for clearing
15 said signal or causing it to go to stop, said means acting in response to a modified signal clearing code to clear said signal only after the reception of a switch control code at said station, and means at said station responsive to a normal or
20 reverse switch control code for operating said track switch to a corresponding normal or reverse position.

13. In a centralized traffic controlling system for railroads; a field station having a track switch and signals for governing traffic thereover with an associated detector track section; a control office having a manually operable switch control lever having normal and reverse positions and a manually operable signal control lever having clear and stop positions; a communication system connecting said control office and said field

station, said system being of the code type for transmitting switch and signal control codes on separate cycles of operation; circuit means for causing said communication system to transmit a switch control code in accordance with the position of said switch control lever on one cycle of operation and to cause the transmission of a signal control code in accordance with said signal lever on another cycle of operation, said means being effective to modify said signal clearing code if said switch control lever is moved to a new position subsequent to the last transmission of a switch control code; a signal clearing relay and a checking relay at said station; a pick-up circuit for said signal clearing relay closed upon the reception of a signal clearing code irrespective of whether such signal clearing code has been modified or not; a stick circuit for said signal clearing relay closed dependent upon the condition of occupancy of said detector track section so as to be opened upon the entrance of a train into such detector track section; a pick-up circuit for said checking relay closed upon the reception of each switch control code; a normally closed stick circuit for said checking relay momentarily opened upon the reception of a modified signal control code; and circuit means including front contacts of said signal clearing relay and said checking relay for clearing said signal.
